UNITED STATES PATENT OFFICE.

WILLIAM L. GARRELS, OF ST. LOUIS, AND CLINTON KIMBALL, OF KIRKWOOD, MISSOURI.

VALVE-GEAR.

SPECIFICATION forming part of Letters Patent No. 665,086, dated January 1, 1901.

Application filed February 26, 1900. Serial No. 6,552. (No model.)

To all whom it may concern:

Be it known that we, WILLIAM L. GARRELS, a resident of the city of St. Louis, and CLINTON KIMBALL, a resident of the city of Kirkwood, St. Louis county, State of Missouri, citizens of the United States, have invented certain new and useful Improvements in Valve-Gears, of which the following is a specification.

Our invention relates to valve-gears, and has for its principal object to obtain constant lead and to substantially equalize all of the events of the stroke—that is, cut-off, release, compression, and preadmission—and to make the events occur in the cylinders at substantially a constant angular distance apart for all possible cut-offs and whether the engine is running forward or backward.

Another object is to avoid the use of eccentrics.

Another object is to provide suitable means for manipulating the valve-gear and throttle-valve.

Another object is to improve generally said valve-gears and manipulating devices.

Our invention consists of the parts and combinations of parts hereinafter described and claimed.

In the accompanying drawings, which form part of this specification, and wherein like symbols refer to like parts wherever they occur, Figure 1 is a vertical side view of our valve-gear applied to a vertical engine looking in the direction of the arrows in Fig. 2. Fig. 2 is a vertical front view, partly sectional, of said gear looking in the direction of the arrows in Fig. 1. Fig. 3 is a cross-sectional detail on the line 3-3 of Fig. 2, showing the means for transmitting motion from one engine to the valve of another engine. Fig. 4 is a detail showing the winged rings mounted on the alined rock-shafts, respectively, and providing means for connecting said rock-shafts to their respective actuating-levers. Fig. 5 is a diagram of our valve motion, wherein the symbols refer to the position of the crank of the engine on the same side of the machine as the parts of the valve-gear shown in full lines in Fig. 1. Fig. 6 is a side view of our device for shifting the radius-rods of the gear equal distances. Fig. 7 is a front view of said device looking in the di-

rection of the arrow in Fig. 5. Fig. 8 is a view of a modified form of said device. Fig. 9 is a plan view of said device mounted on a motor-vehicle. Fig. 10 is a detail view showing means for manipulating the valve-gear and throttle-valve.

For convenience of reference the parts on one side of the engine (shown in Fig. 1 in full lines) are designated by capital letters, whereas the corresponding parts on the other side of the engine (shown in Fig. 1 in broken lines) are designated by corresponding small letters. The cross-head G, Fig. 1, however, shown in dotted lines is on the same side as the parts of the valve-gear shown in full lines.

Our valve-gear is arranged for use in connection with two or more separate engines or with an engine having parallel cylinders. The valve for each cylinder or engine is connected to the reciprocating parts of both engines in such a way that the motion of each valve is substantially symmetrical with respect to the motion of the piston of its engine—that is, the curve whose coördinates represent corresponding positions of the valve and the piston approximates an ellipse. The connections of one valve are similar to those of another valve, although there are certain obvious differences in detail arising from different locations of the parts. The valve-rod A is connected by a pin B to a floating lever C. This lever C is connected, by means of a rod D, to a rock-lever E, and this lever E is in turn connected, by means of a rod F, to the cross-head of the same engine to which the valve-stem A belongs. The movement of the cross-head thus communicates a definite reciprocating motion to the valve of its engine, which motion is predetermined by the arrangement of the intermediate connecting devices, so as to overcome the lap and lead of the valve and contribute the constant component of the valve motion. The characteristic of the motion of the cross-head is that it is rapid in the middle of its stroke and slow at the end of its stroke. By the construction just described this characteristic motion is transmitted to the valve, so that the opening and the closing thereof are effected with a quick movement.

The fulcrum of the combination-lever C is

carried and constituted by the end H of a rod I. This rod I carries a block K, pivotally fastened thereto, and this block fits or slides on a curved link L, which is mounted on a rock-shaft M, arranged to be actuated by the cross-head or other moving part of the other engine. The rock-shaft M is fixed to a winged ring N, which in turn is fixed to a flange or collar mounted on the hub of the rock-lever connected to the cross-head of the other engine. Hence the cross-head g (not shown) imparts a rocking motion to the link L, which supplies the variable component of the valve motion—that is, the variable component of the valve motion for one engine is derived from the cross-head of the other engine. The rocking of the link L imparts to the radius-rod I a reciprocating motion, which varies according to the position of the block K along said link. When the block K is in mid-position, the rocking of the link imparts no motion of translation to the radius-rod. The extent of said motion increases with the distance of the block K from its mid-position, and its direction varies according as the block K is shifted toward one end or the other of the link.

For the purpose of shifting the block K along the curved link and properly guiding said block in its to-and-fro movement the following construction is used: The radius-rod I is extended beyond the block K and is provided with a collar or guide O, in which said rod glides freely, the principal function of the guides or collars O o being to guide the pins in the blocks K k in substantially right lines, and thereby increase the symmetry of the elliptic diagrams. The collar O is pivotally mounted on one arm of a tumbling-shaft P, fulcrumed in the framework. The other arm of the tumbling-shaft has a reach-rod Q connected thereto, and the end of the rod is connected to a block Q'', adapted to slide in a straight guide provided therefor. Similar connecting devices connect the rod i to this guided block, and the block has a rod connected to a crank-arm R on a counter-shaft S, adapted to be manipulated by the operator or attendant. Obviously any means for shifting the collars O o, so that the blocks K k are shifted along the links L l equal distances from the middle of said links and in opposite directions, will correctly control the cut-off and may be substituted for that just described.

It is desirable in order to secure the same motion for the two valves to arrange the rock-shafts in alinement. For this purpose the construction illustrated in Figs. 2, 3, and 4 is especially adapted. The lever E has a horizontal cylindrical hub E'. At the end of this hub is an outwardly-extending flange. Fastened flatwise on this flange is a plate N, having a circular hole concentric with the hub E'. In this hole is pinned or otherwise fastened the end of a cylinder or pin m, constituting the rock-shaft, and to this rock-shaft is fixed the curved link l for imparting the variable

motion or throw to the valve of the opposite engine. In like manner the rock-shaft M for imparting motion to the link L, and through it to the valve-rod A, is connected to its actuating-lever e, the connections of said levers E e to the respective engines being similar, so as to secure identity for the movements of the links L l. The arrangement of the parts is such that each rock-shaft M m lies concentrically inside of the hubs E' e', and said rock-shafts are therefore in alinement with each other and are independently movable. So, too, the levers E e are pivoted concentrically with each other and with said rock-shafts M m. It is preferable to provide a bush M' m' for each of the rock-shafts. In like manner bushes E'' e'' are provided for the hubs E' e', which bushes are incased in the hanger J, fixedly secured to the framework. This hanger is made of two parts, fastened together by means of bolts, as shown in Fig. 3.

The curve of the link L is a circular arc whose center (when the link is in its middle position 0 or 10, Fig. 5) is the pivot or fulcrum H of the combination-lever C. The middle point of the travel of the pivot or fulcrum H (0 or 10, Fig. 5) is thus fixed for all positions of the radius-rod I so long as the link L remains in its middle position (0 or 10, Fig. 5)—that is to say, in this middle position of said link the block may be shifted to any desired position along the link without changing the position of the fulcrum-pin H. The middle positions 0 and 10 of the fulcrum H being a fixed point, the corresponding positions 0 and 10 of the pin connecting the combination-lever C to the rod I are fixed points for all cut-offs whether the engine is running forward or backward. Consequently the corresponding positions 0 and 10 of the pin B of the valve-rod are likewise fixed points. The parts are so connected that whenever the piston is at the end of its stroke the pin B is at one or the other of the two points 0 or 10, which points are fixed for all cut-offs. It follows that the lead of the valve is mathematically constant for all cut-offs whether the engine is running forward or backward.

As will be apparent upon inspection of the elliptic valve diagrams in Fig. 5, when the cut-off is reduced the curve whose coördinates represent corresponding positions of the valve and of the piston and whose ideal is a true ellipse approaches a right line (the true limiting-case of an ellipse) and becomes a right line when the engines are on center—that is, when the block K is in the middle of its travel. Heretofore in all valve-gears in which the variable component of the valve motion is obtained from one source and the constant component from another this limit has been a curve. The elliptic curves for our valve diagram indicative of the efficiency of the gear approach nearer the ideal true ellipse than is the case with older gears, and thus evidence greater economy of the engine. The maximum error in the occurrence of any event

of the stroke for any cut-off, whether the engine is running forward or backward, as shown by the elliptic diagrams of Fig. 5, does not exceed 2.2 per cent. of the stroke.

5 As shown in Fig. 5, the difference between the two sets of curves is practically *nil*; but whatever this difference may be the set of elliptic curves which represent the movement of one valve when the engines are running forward represent also mathematically the movement of the other valve when the engines are running backward.

The difference in the effective piston areas due to the presence of the piston-rod may be corrected by properly reducing the steam-lap 15 on the crank end of the valve.

Our valve-gear is especially applicable to locomotives and marine engines. It is herein described as applied to a steam-driven road- 20 vehicle.

A convenient means for manipulating the counter-shaft S, especially adapted for motor- 25 vehicles, is illustrated in Figs. 9 and 10. In this construction the counter-shaft S is journaled in the engine-frame and has a crank-arm fixed thereto, which crank-arm is connected by a rod T to another crank-arm fixed to a tubular reversing-lever shaft V, journaled in the vehicle-body. The tubular reversing-lever shaft has a crank-arm or reversing-lever V extending upwardly within convenient reach of the operator. The lever V consequently controls the cut-off of the engine and may be arranged to run the vehicle forward when it is moved forward from the center position and to run the vehicle backward when it is moved backward from the center position. In order to maintain the gear in any position to which it may be adjusted, a sector W, having a series of notches 30 or depressions, is mounted on the counter-shaft S or on the framework of the engine concentrically with the counter-shaft and an arm mounted on said framework or counter-shaft which has a spring pressed therein whose end is curved or beveled to fit into the notches of the series. The pin, by reason of its curved or beveled end, will yield to the forces applied for manipulating the valve-gear, but is strong enough to steady the valve-gear in any position to which it may be adjusted. If the engine is pivotally mounted on the body so that it may swing independently of the same, mounting the spring-pressed pin and sector W on the engine-frame or counter-shaft S eliminates the motion of the engine with respect to the body in controlling the cut-off. In other words, if the engine moves in its pivotal mounting with respect to the body the cut-off is not effected thereby.

The handle X of the cut-off-controlling lever V is pivotally mounted thereon to swing in a plane at right angles to the plane of the motion of said lever V. The handle has an 65 arm fixed thereto which is connected by a rod to a bell-crank Y, journaled in a part of the lever V. The bell-crank is connected to an-

other rod incased in the hollow shaft U by a universal joint. This rod is in turn connected by a universal joint to a crank-arm which extends through a slot provided for the purpose in the hollow shaft U. The shaft Z of this crank-arm has another crank-arm which connects to a link adapted to impart motion to the throttle-valve. It is desirable to use 70 a throttle-valve which always tends to close, so that it can be either held in position like the valve-gear or by throwing a spring-pressed pin W' out of action it will close automatically if not held open by pressure on the handle X. With the above-described manipulating device the cut-off and throttle are independently controlled from one handle, the controlling motions being convenient and natural.

Fig. 8 illustrates a modification for shifting the radius-rods. In this modification the rock-shafts M' m' are not in alinement. In this construction the radius-rods I' i' run, respectively, in slides O' o', which are respectively 75 connected by reach-rods Q' q' to a crank-arm R', mounted on a counter-shaft S'. The resulting movement approximates the movement above described.

Our invention is applicable to marine and 80 other compound engines and is especially adapted for motor-vehicles.

What we claim is—

1. In a valve-gear for a plurality of engines, a rock-lever connected to a moving part of one 85 of the engines and a second rock-lever connected to a moving part of the other engine, said rock-levers being mounted concentrically and being each operatively connected to the valves of both engines by a permanent 90 and an adjustable connection respectively, substantially as described.

2. In a valve-gear for a plurality of engines, a rock-lever connected to a moving part of one 95 of the engines and a second rock-lever connected to a moving part of the other engine, and concentrically-mounted links each operatively connected to one of the engine-valves, said rock-levers being mounted concentrically and being each connected to one of said 105 links and to the engine-valve to which the other link is connected, substantially as described.

3. In a valve-gear for a plurality of engines, concentrically-mounted rock-levers connected 110 respectively to moving parts of the engines, links mounted concentrically with and respectively connected to said rock-levers and to the engine-valves, said rock-levers being 115 each connected to the engine-valve to which the link of the other lever is connected, substantially as described.

4. In a valve-gear for a plurality of engines, a rock-lever connected to a moving part of one 120 of the engines and a second rock-lever connected to a moving part of the other engine, said rock-levers being mounted concentrically and being each operatively connected to the 125 valves of both engines, each of said rock-

levers being operatively connected to a rod and means for guiding said rod so that its point of connection to said lever moves in a substantially straight line, substantially as shown in Fig. 3.

5 described.

5. In a valve-gear for a plurality of engines, a rock-lever connected to a moving part of one of the engines, and a second rock-lever connected to a moving part of the other engine, 10 and concentrically-mounted links each operatively connected to one of the engine-valves, said rock-levers being mounted concentrically and being each connected to one of said links and to the engine-valve to which the 15 other link is connected, said links being each connected to a rod so that its point of connection to said link moves in a substantially straight line, substantially as described.

6. In a valve-gear for a plurality of engines,
20 concentrically-mounted rock-levers connect-
ed respectively to moving parts of the en-
gines, links mounted concentrically with and
respectively connected to said rock-levers and
to the engine-valves, said rock-levers being
25 each connected to the engine-valve to which
the link of the other lever is connected, said
links being each connected to a rod so that its
point of connection to said link moves in a
substantially straight line, substantially as
30 described.

7. A valve-gear for a plurality of cylinders comprising floating levers each connected to a different valve and connected through intermediate connecting devices to different moving parts of the engine, a rod for each of said levers constituting the fulcrum thereof, concentric rock-shafts connected by similar connecting devices to said moving parts respectively, each of said rock-shafts being operatively connected with the radius-rod of the lever which is connected to the moving part from which the other rock-shaft is actuated, substantially as described.

8. A valve-gear for a plurality of cylinders comprising two floating levers each connected to a different valve and connected through intermediate connecting devices to different moving parts of the engine, a rod for each of said levers constituting the fulcrum thereof, two concentric rock-shafts connected by similar connecting devices to said moving parts respectively and a curved link on each of said rock-shafts, each of said links being operatively connected with the radius-rod of the lever which is connected to the moving part from which the other curved link is actuated, substantially as described.

9. A valve-gear for a plurality of cylinders comprising two floating levers, each connected to a different valve and connected through intermediate connecting devices to different moving parts of the engine, a rod for each of said levers constituting the fulcrum thereof, two concentric rock-shafts connected by similar connecting devices to said moving parts respectively, said rods being operatively connected to said rock-shafts and means for guid-

ing each of said rods so that at its point of connection to said shaft it moves in a substantially straight line, substantially as described. 70

10. A valve-gear for a plurality of cylinders comprising two floating levers each connected to a different valve and connected through intermediate connecting devices to different moving parts of the engine, a rod for each of said levers constituting the fulcrum thereof, rock-shafts connected by suitable connecting devices to said moving parts respectively, and a curved link on each of said rock-shafts, each of said links being operatively connected to the radius-rod of the lever which is connected to the moving part from which the other curved link is actuated, and a counter-shaft having an arm, tumbling-shafts each mounted on a fixed axis and connected to said arm and carrying a guide for one of said radius-rods, said rods and tumbling-shafts being proportioned and arranged to shift said radius-rods equal angular distances in opposite directions, substantially as described. 75 80 85 90

11. A valve-gear for a plurality of cylinders comprising floating levers each connected to a different valve and connected through intermediate connecting devices to different moving parts of the engine, a rod for each of said levers constituting the fulcrum thereof, rock-shafts connected by suitable connecting devices to said moving parts respectively, each of said rock-shafts being operatively connected to the radius-rod of the lever which is connected to the moving part from which the other rock-shaft is actuated, a counter-shaft having an arm, a rod connected thereto, straight guides for said rod, tumbling-shafts carrying guides for said radius-rods, and reach-rods connecting said tumbling-shafts to said first-mentioned rod, substantially as described.

12. A valve-gear for a plurality of cylinders 110 comprising floating levers each connected to a different valve and connected through intermediate connecting devices to different moving parts of the engine, a rod for each of said levers constituting the fulcrum thereof, 115 concentric rock-shafts connected by suitable connecting devices to said moving parts respectively, each of said rock-shafts being operatively connected to the radius-rod of the lever which is connected to the moving part from which the other rock-shaft is actuated, a counter-shaft having an arm, a rod connected thereto, tumbling-shafts mounted on a common axis carrying guides for said radius-rods, a guide for said rod arranged radially to said axis and reach-rods connecting said tumbling-shafts to said first-mentioned rod, substantially as described. 120 125

13. A valve-gear for a plurality of cylinders comprising floating levers each connected to a different valve and connected through intermediate connecting devices to different moving parts of the engine, a rod for each of said levers constituting the fulcrum there-

of, concentric rock-shafts connected by suitable connecting devices to said moving parts respectively, each of said rock-shafts being operatively connected to the radius-rod of the lever which is connected to the moving part from which the other rock-shaft is actuated, a counter-shaft having an arm, tumbling-shafts mounted on a common axis and carrying guides for said radius-rods and rods for connecting said tumbling-shafts to said arm, and means for guiding said rods in a straight line radially to the axis of said tumbling-shafts, substantially as described.

14. A valve-gear for a plurality of engines wherein the valve motion is derived partly from one engine and partly from another, comprising concentric rock-shafts actuated independently of one another by the respective engines acting through similar connecting devices and each arranged to actuate the valve of another engine, substantially as described.

15. A valve-gear for a plurality of engines comprising means for connecting each valve to a moving part of its engine, concentric rock-shafts actuated independently by the respective engines acting through similar connecting devices and each connected to the valve-operating means of another engine to 30 actuate the same, substantially as described.

16. A valve-gear for a plurality of engines comprising means for connecting each valve to a moving part of its engine, levers connected to moving parts of the respective engines and having flanged hubs, winged rings fastened to said levers, and alined rock-shafts fastened to said winged rings and each carrying a link connected to the mechanism for actuating the valve of a different engine 40 from that which actuates said rock-shaft, substantially as described.

17. A valve-operating mechanism comprising a valve-gear and a counter-shaft for actuating the same, and means for holding said counter-shaft in any desired position, a tumbling-shaft, arms fixed to said counter-shaft and said tumbling-shafts and rods connecting them, and means for manipulating said counter-shaft, substantially as described.

18. A valve-operating mechanism comprising a valve-gear and a counter-shaft for actuating the same, a yielding spring-actuated pin mounted on said counter-shaft, a sector to coöperate with said pin, a tumbling-shaft 55 an arm fixed to said counter-shaft and rods connecting them and means for manipulating said counter-shaft, substantially as described.

19. A valve-operating mechanism comprising a valve-gear and a shaft operatively connected thereto and a hand-lever fixed to said shaft and having a handle pivoted to swing

at right angles to the direction of motion of the lever and operatively connected to a valve or controlling device, substantially as described. 65

20. A valve-operating mechanism comprising a valve-gear and a counter-shaft for actuating the same, a shaft, crank-arms fixed to said counter-shaft and to said shaft respectively a rod connecting them, a hand-lever fixed to said shaft and having a handle pivoted to swing at right angles to the direction of motion of the lever and operatively connected to a valve or controlling device, substantially as described. 75

21. A valve-operating mechanism comprising a valve-gear and a counter-shaft for actuating the same, a hollow shaft, crank-arms fixed to said counter-shaft and to said hollow shaft respectively, and a rod connecting said crank-arms, a hand-lever fixed to said shaft and having a bell-crank handle pivoted to swing at right angles to the direction of motion of the lever, a bell-crank near the end of the shaft, a rod connecting said handle to said bell-crank, a second rod inside of said shaft connected to said bell-crank and connected through suitable connecting devices to a valve or controlling device, substantially as described. 80 90

22. A valve-gear for a plurality of cylinders comprising two floating levers each connected to a different valve and connected through intermediate connecting devices to different moving parts of the engine, a rod for each of said levers, constituting the fulcrum thereof, rock-shafts connected by suitable connecting devices to said moving parts respectively, each of said rock-shafts being operatively connected to the radius-rod of the lever which is connected to the moving part from which the other rock-shaft is actuated, and a counter-shaft having a crank-arm, tumbling-shafts each mounted on a fixed axis and connected by rods to said crank-arm and carrying a guide for one of said radius-rods, said rods and tumbling-shafts being proportioned and arranged to shift said radius-rods substantially equal angular distances in opposite directions, substantially as described. 105 110

23. A valve-operating mechanism comprising a valve-gear and a counter-shaft for actuating the same and means for holding said counter-shaft in any desired position, and means for manipulating said shaft, the means for manipulating said shaft being movable independently of said shaft, substantially as described. 115
